Primary Examiner — Melody Brown(74) *Attorney, Agent, or Firm* — Finnegan, Henderson, Farabow, Garrett & Dunner, LLP(57) **CLAIM**

The ornamental design for a grill opening for a truck, as shown and described.

DESCRIPTION

FIG. 1 is a perspective view of a grill opening for a truck showing our new design; and,

FIG. 2 is a front elevation view thereof.

The broken lines of the truck are included for the purposes of illustrating environmental structure and form no part of the claimed design.

1 Claim, 2 Drawing Sheets(56)
